LOCOMOTIVE.

Application filed April 2, 1923, Serial No. 629,411, and in Germany June 24, 1922.

This invention relates to locomotives the fire of which is continually revived by suctional draught, and it has for its primary object to provide a locomotive of this kind with which a feed-water heater is arranged in the channel connecting the blower with the smoke box.

An embodiment of the subject matter of the invention is diagrammatically illustrated in the accompanying drawings, in which—

Fig. 1 is a side elevation of the locomotive, and

Fig. 2 a front elevation corresponding to Fig. 1, partly in section along the line 2—2 of Fig. 1.

Fig. 3 is a top plan view of Fig. 1, partly in section.

The smoke box A (Fig. 1) of the locomotive boiler is divided by a partition a^1 into two halves and a channel B extends from the rear half along one side of the boiler to the casing c^1 of the heater C which is fastened to the locomotive frame underneath the boiler transversely with relation to the longitudinal axis of the locomotive. Disposed laterally of the casing c^1 is a water chamber which is divided into two chambers c^2 and c^3 (Fig. 2). The ends of one branch of a nest of pipes D, bent into U-shape, open into the chambers c^2 , while the ends of the other branch open into the chamber c^3 . The chamber c^2 is connected to the feed-water supply pipe and the chamber c^3 to the feed-water delivery pipe. At the side of the locomotive opposite to that at which the channel B is arranged, the heater C is connected directly to the suction branch e^1 of a mechanically driven blower E which blows into a channel F. The channel F opens into the front portion of the smoke box A which is in communication with the chimney.

The suctional action of the blower E draws the flue gases from the rear portion of the smoke box A through the channel B into the heater C, wherein they wash the nest of pipes D and transmit part of their heat to the feed-water flowing through the same. The flue gases pass from the heater through the blower E into the channel F and further into the front portion of the

smoke box A from which they are ejected through the chimney.

On passing through the feed-water heater, the flue gases are strongly cooled so that they will possess a relatively low temperature when entering the blower. At the same time, the work necessary for driving the blower is reduced on account of the reduction of the volume of the flue gases caused by the cooling of the same. Besides, the arrangement of the blower at the place where the flue gases are led underneath the boiler transversely with relation to the longitudinal axis of the locomotive, produces the advantage that the admission and exhaust of the gases into and out of the blower can take place readily.

Claims:

1. In combination with a locomotive comprising a boiler and smoke box, a blower for continually reviving the fire by suctional draught and a flue gas channel extending first from the smoke box in a rearward direction along one side and outside of the boiler, then transversely underneath the boiler and further in a forward direction along the other side and outside of the boiler to the chimney, a feed-water heater being arranged in the portion of the flue gas channel extending transversely with relation to the longitudinal axis of the locomotive.

2. In a locomotive, a boiler, a smoke box, a blower for continually reviving the fire by suctional draught and a flue gas channel extending first from the smoke box in a rearward direction along one side and outside of the boiler, then transversely underneath the boiler, and further in a forward direction along the other side and outside of the boiler to the chimney, a feed-water heater being arranged in the portion of the flue gas channel extending transversely with relation to the longitudinal axis of the locomotive, the blower being likewise arranged at that transverse portion in the part of the flue gas channel extending in a forward direction to the chimney.

The foregoing specification signed at 100 Cologne, Germany, this 12th day of March, 1923.

REINHARD KLINGELHÖFFER.
